UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED ADDING AND TYPEWRITING MACHINE.

1,339,796.

Specification of Letters Patent. Patented May 11, 1920.

Application filed October 18, 1918. Serial No. 258,695.

To all whom it may concern:

Be it known that I, BURNHAM C. STICKNEY, a citizen of the United States, residing in Elizabeth, in the county of Union and State of New Jersey, have invented certain new and useful Improvements in Combined Adding and Typewriting Machines, of which the following is a specification.

This invention relates to combined adding and typewriting machines, and is illustrated in connection with the machines of the type disclosed in the patent to Hart 1,270,411.

It is usual in these machines to provide a dog for selecting the denominations in the computing mechanism; said dog being usually mounted upon the typewriter carriage, and coöperating with the numeral type keys, which set up index pins in different denominations, as the latter are selected one after another by the dog, during the step-by-step feeding movement of the typewriter carriage.

For coöperation with the dog to this end, there is provided a set of denomination jacks, which are displaceable individually by said dog as the carriage carries the dog past the jacks. Each jack displaces a row of index pins of the same denomination as the jack; and during such displacement any numeral type key may be actuated to print the type and set up the corresponding index pin in the displaced row.

It is customary to use two or more totalizers or registers, and two or more sets of jacks to correspond, and, if desired, a single dog may operate the jacks in one set during that portion of a computing operation which is performed by the keys, and then said dog may, during the subsequent travel of the carriage, operate the jacks in another set, etc. Since each register usually comprises nine or more number wheels, and, therefore, requires nine or more jacks, and since the dog must traverse all of the jacks in one set before those in the next set can be traversed, it follows that the columns upon the work-sheet cannot be placed as closely together as is desirable, especially when the columns are narrow, as when the column contains say only three decimal places. In other words, a narrow column must occupy as much of the width of the work-sheet as is used by a column having many more decimal places.

One of the objects of the invention is to

permit the writing of narrow columns 55 closely together upon the work-sheet without reducing the number of jacks or the number of wheels in the registers. If desired, one or all of the registers can then be used for wide-column work.

In carrying out this feature of the invention, in a machine having say two registers of nine dials each, there are provided two denomination-selecting dogs, one of which is capable of operating only say three jacks 60 of lowest denominations for one of the totalizers or registers, while the other dog is capable of operating only say three jacks of the lowest denominations for the other of the registers. In other words, each dog 65 will not only pass freely all of the jacks in the other set, but will also skip all of the jacks in its own set, except the lowest three. It is obvious, however, that the number of jacks controlled by each dog can be less or 70 more than three, as may be required.

A denomination-selecting dog is usually adjustable to different letter-space positions along the carriage; and the novel dogs herein disclosed may be relatively adjusted so 75 that while the first column is being typed upon the work-sheet, the corresponding dog will engage and displace the lowest three jacks for one register, so that the number in one column is both printed and set up, 80 and so that a number may be then typed in a second column close to the first, while the second dog displaces successively the three lowest jacks for its register, even though said register may have many more jacks.

If it were attempted to accomplish this purpose in the ordinary machine, it would be found that while the first dog was displacing jacks for its register, the second dog would also be displacing jacks for the second register, and hence index pins would be set up simultaneously for both registers, while typing a number in only one column. Hence, the digits typed in the first column would be added in the second register to the 85 numbers typed in the second column. In order to overcome this and other difficulties, I provide a cam device which automatically, during the advance of the carriage, lifts the first dog into effective position only when 90 it is in register with the three lowest dogs for its register; both dogs being normally down out of effective position, that is, being

normally so far depressed that they cannot reach any jack in any register. Upon the dog itself is preferably mounted a cam whose effective length is about equal to three 5 or four letter-feeding movements of the typewriter carriage, this cam being so placed that it will be lifted and held up by means of a stationary cam, which is individual to the set of jacks, while the dog is traversing 10 the three or four lowest jacks, which are thus operated. Likewise, the second dog is provided with a three or four-space cam, to coöperate with a second stationary cam, which is individual to the second set of 15 jacks. Thus, it will be seen that even though the registers may be each of nine or more denominations, still only three or four denominations of each thereof will be brought into use by the dogs, so that narrow 20 columns may be typed in juxtaposition upon the work-sheet, and the numbers typed in the first column will be added only in the first register, while those typed in the second column will be added only in the second 25 register.

Whenever desired, either register may be used to its full capacity, by substituting a dog having a displacement cam which is equal in extent to the entire set of jacks, 30 say nine letter-spaces of the typewriter carriage; or both dogs may have full-capacity cams. Any dog is not only adjustable along the carriage, but also movable far to the left or right out of range of any totalizer, or 35 removable from the machine when not required, as disclosed in Hart Patent 1,176,364. A complement of dogs, some of which have short, others of which have medium, and still others of which have maximum length 40 elevating or cocking cams, will, therefore, impart flexibility or adaptability to the machine, enabling each register to be used for a very narrow column, or for medium width, or for a very wide column, regardless of 45 the width of the column for which the other register is used, and permitting all columns to be typed as closely together as desired. It is further noted that this may be accomplished by a very simple and inexpensive 50 change in existing machines of the Underwood-Hanson type, illustrated in the patents herein mentioned. It will be understood that three, four or more registers may be employed, with corresponding sets of jacks, 55 and that the jacks for each register may differ from those for any of the other registers, as illustrated for example in the patents to Hart 1,190,171, 1,190,233 and 1,231,523, in which the jacks for the second 60 register are longer than those for the first, and the jacks for the third register are longer than those for the second; the respective dogs being out of line with one another or in echelon arrangement, so that 65 the dog for the first register will not affect

the jacks for the second and third registers, while the dog for the second register will not affect the jacks of the first or third registers, and so on. Hence all the dogs as so far described may be elevated by their 70 cams when traversing all the jacks, but each dog will operate only its own jacks; the number of its jacks that are operated being dependent in each instance upon the length of the elevating cam provided upon that 75 particular dog.

It will be further understood that cross-adding may be simultaneously performed by the use of a third register, having a succession of the described dogs for operating the 80 denomination jacks thereof, there being as many cross-adding dogs as there are columns to be cross-added; and that these cross-adding dogs may each be provided with an elevating cam of suitable length to meet the 85 requirements of the case, short-cam dogs being used for numbers of few denominations, and being locatable close to one another, to agree with the spacing of the columns upon the work-sheet. Hence, al- 90 though all of the registers may be of large capacity, still narrow columns may be typed closely together upon the work-sheet, and the numbers therein may be added vertically, while cross-addition of such numbers may be 95 made at the same time in the cross-adder. When desired, the machine may be used for writing and adding only wide columns, or both wide and narrow columns, with the 100 columns spaced as closely together as desired on the sheet, while the results of the cross-additions will show in the cross-adder or grand-total register.

Another feature of the invention relates to increasing the adaptability of the machine 105 in still another way, which is, by making it practicable to compute separately in a single large totalizer two or more narrow columns of numbers, while permitting such columns, if desired, to be typed closely side by side 110 upon the work-sheet. To this end, a separate denomination-selecting dog is provided for each of the narrow columns, and each of these dogs is in line with all of the jacks in its own register, although preferably out 115 of line with jacks upon other registers; and in carrying out this feature of the invention, one dog is used for say the lowest three denominations in the register, a second dog is used for say three denominations at the 120 middle portion of the register, and a third dog may be used for say three denominations at the highest portion of the register; the register for this purpose having preferably eleven or more denominations. When 125 used in this way, the register would be the equivalent of three separate registers each having the denominations of units, tens, hundreds, and perhaps thousands. In order to confine the activity of each dog to its own 130

portion of the register, the elevating cam upon the second dog is staggered or placed out of line with reference to the cam upon the first dog; and the cam upon the third dog is placed out of line with reference to the cams upon the first and second dogs. Hence, the various cams have a staggered or echelon relation, and each dog can, therefore, operate only its own three jacks; it being understood that this register has three stationary cams, and that they are arranged to correspond with the elevating cams upon the dogs; one stationary cam being placed at the lowest portion of the set of jacks, another stationary cam out of line with the first and arranged at the middle portion of the set of jacks; and a third stationary cam out of line with the two others and arranged at the upper portion of the set of jacks. It will thus be seen that these three dogs may be assembled closely together to permit the close typing of the columns upon the work-sheet, and thus that a single register may be used for adding separate columns written side by side. The number of such columns may, of course, be more or less than three, and the number of denominations in each column may be more or less than three. At any time by substituting a dog having a long elevating cam, the same totalizer may be used for adding numbers of many more denominations typed in a single wide column upon the work-sheet.

It will be seen that as to certain relevant features, this invention presents advantages over the invention disclosed in the Griffith Patent 1,263,881, since the present device has greater adaptability and is easily made and applied to existing machines, and enables the jacks to be of uniform length throughout for each register, so as to be capable of use with all lengths of elevating cams; so that the register need not remain permanently split; while the advantage is preserved of using different lengths of jacks for different registers, each whereof may or may not be splittable by means of the described disaligned or offset elevating cams.

It will be further understood that the aforesaid cross-adding mechanism can be used to cross-add the narrow columns, which are added vertically in a single totalizer in the manner just described.

It will be further understood that while one totalizer or register may be used for adding separately two or more columns, another register may be used for adding still another column, or for adding two or more narrow columns in the manner just described, so that, for example, six narrow columns may be written closely side by side upon the work-sheet and added vertically by the use of only two totalizers, thus greatly increasing the adaptability and capacity of the machine; three totalizers af-

fording means for adding nine narrow columns, and so on; while upon a cross-adder as many of the narrow and wide columns may be cross-added at the same time as may be desired; the dogs and jacks for the cross-adder being preferably out of line with all of the dogs and jacks of the other registers. The extreme right-hand register may be used for the cross-adder, and the rack which carries all of the dogs may be extended to the right as far as necessary in order to give room for the location of as many dogs as are required for operating the cross-adder for the required number of columns.

The invention may be also employed in some cases to perform both vertical and cross-addition of narrow columns in a single totalizer, which preferably may have twelve or more denominations. The first dog could operate say the three lowest jacks for adding the numbers in one column vertically; the second dog could be used for operating three or more jacks in the middle portion of the set, for adding vertically the numbers in the other column which is to be cross-added; and an additional dog or dogs could be employed for operating the jacks at the highest part of the register, so that these highest jacks are operated once for each of said two columns. It will be further understood that while one totalizer is being operated in this manner, a similar totalizer can be operated for adding vertically and cross-adding the numbers written in other columns on the same work-sheet, and so on.

When it is desired simply to cross-add without adding any column vertically, very many narrow columns may be typed closely side by side upon the work-sheet, and the denomination-selecting dogs, one for each column, may be set sufficiently close together, since each dog may have a short elevating cam; or, if desired, wide and narrow columns may alternate on the page, the dogs having elevating cams of corresponding lengths.

Other features and advantages will hereinafter appear.

In the accompanying drawings.

Figure 1 is a diagrammatic view to illustrate how the machine may be readily equipped for both vertical and cross-adding in a single split register.

Fig. 2 is a diagram to illustrate a method to permit narrow columns to be typed closely together upon a work-sheet and added in wide registers without difficulty.

Fig. 2^a shows side elevations of different forms of denomination-selecting dogs.

Fig. 2^b shows another form of selecting dog for operating the jacks in different portions of a split totalizer under certain circumstances.

Fig. 3 is a sectional side elevation of a

combined typewriting and computing machine of the well-known Underwood-Hanson type.

Fig. 4 is a part sectional rear elevation or diagram of the upper portion of a combined typewriting and computing machine, and illustrates a method of equipping the machine so that numbers added in two totalizers may be cross-added in a third totalizer, and so that separate vertical addition may be performed in another portion of one of said totalizers.

Fig. 5 is a diagram to illustrate cross-adding in one totalizer of numbers written in two other totalizers in a manner to permit the close typing of columns upon a page even though the registers are of great width.

Fig. 6 is a diagram to illustrate the cross-adding in one totalizer of three narrow columns of numbers which are vertically added by means of another register.

Fig. 7 illustrates the manner of adding numbers in two large totalizers which are typed in six closely assembled columns on the work-sheet.

Fig. 7a is a detail view of one of the cam-carrying bails.

Fig. 8 is a part sectional plan of devices seen at Fig. 4.

As described in said patents, the typewriting mechanism comprises numeral keys 10 and alphabet keys 11 which are connected by levers 12 to type-bars 13 to throw the latter against the platen 14, which is mounted upon a carriage 15. For the purpose of letter-feeding, the carriage is provided with a rack 16 which is connected by a pinion 17 to an escapement wheel 18, which is controlled by dogs 19, the latter moved by a universal bar 20, which is operated by the type-bars. The carriage feeds step by step under the influence of a driving spring (not shown) at the operation of the type keys.

As also set forth in said patents, the Underwood-Hanson machine comprises computing mechanism connected with the numeral keys 10, said keys having stems 21 which operate arms 22 upon rock shafts 23, the latter connected to transverse horizontal bars 24 which are movable downwardly for the purpose of depressing or "setting up" index pins 25 when the keys are depressed. The index pins are arranged in rows, nine in each row, there being as many rows as there are denominations in the register. Each row of index pins is mounted upon a movable bar 26. These bars are placed side by side and extend forwardly and rearwardly. The index pins are normally out of range of any of said transverse bars 24 but any row may be moved into range of all of said bars 24. These movements or displacements of the index-pin bars 26 are effected automatically by the typewriter carriage. For this purpose, there is mounted upon the carriage a

denomination-selecting dog 27, which, during the movement of the carriage, will lift, one after another, all the jacks 28 in a set, said jacks being mounted at the rear of the machine, and being in the form of levers whose rear arms depress rods 29, which are connected by levers 30 and a transposition device 31 to bell cranks 32 arranged in rear of the bars 26 which carry the index pins 25; the operation being that when the selecting dog 27 on the carriage strikes any denomination jack 28, the latter is lifted and its rear end depressed, thus carrying down the link 29 and moving the corresponding member of the transportation device 31, to rock the associated bell crank 32, whose upright arm presses forwardly the bar 26 which carries the index pins 25 of the same denomination as the jack 28 which is so actuated. Hence, all of the index pins on said bar 26 are brought into range of the key-operated cross-bars 24, to enable the latter to set any pin in this row. After all the index pins have thus been set up for any number, the bars 26 are all driven forwardly by means of the set-up pins, and by means of gears 33 at their front ends revolve dials 34, of which there are usually nine or more in the register. This movement of the rack bars is effected by a general operator 35, which may be operated either manually or by power, and is in some cases operated automatically, as set forth in said patents, and others.

The denomination-selecting dog 27 is in ineffective position except when the typewriter carriage 15 is in a computing zone, that is, in such a position that the numbers typed upon the work-sheet may be computed by the register. To enable it to move into and out of effective position, the dog 27 is carried upon a mount 36 which can swing up and down upon a horizontal rod 37, which is fixed to the typewriter carriage. Moreover, the dog with its mount may be adjusted along said rod, and may be accurately located by means of one or more teeth 38 depending therefrom in position to engage the teeth of a horizontal rack 39 which also extends along the carriage. Up-and-down movement of a dog into and out of effective position is disclosed in Gumprecht Patent 1,268,565, and Thornton Patent 1,238,055, etc., but in said patents the movement of the dog into effective position is controlled by a stationary cam which extends the entire length of the set of jacks, to raise the dog during its entire movement past the set of jacks. Hence, if two dogs in said patents were adjusted closely together, both would become effective upon jacks in the same register at the same time, resulting in erroneous calculations; whereas the present invention provides means

whereby two dogs may be traversing the same set of jacks while only one of those dogs will be effective upon any of the jacks. This result is accomplished by providing an elevating or cocking cam 40 upon the dog, whose length or span determines the number of jacks that it is desired said dog to operate, but has no control over the number of jacks that shall be operated by any other dog. In said patents, a single cam determined for every dog how many jacks the dog should operate; whereas in the present case, each dog has its own independent determining means. The stationary cam or shoulder 41 has no substantial length, and hence can coöperate with elevating cams of different lengths upon different dogs. The dog cam 40 is preferably in the form of a roller extending horizontally in the direction of the travel of the carriage, and pivoted in ears 42 formed in a bracket 43 which depends from the dog mount 36; while the stationary cam 41 is preferably in the form of a wheel which is mounted upon a forwardly extending horizontal pivot carried by a stationary bar or support 44, that is, a bar which does not travel with the carriage. The dog, its elevating cam and the stationary cam may be so placed that the elevating cam will ride off from the stationary cam just as the dog passes or relinquishes the jack of lowest denomination; the length of the elevating cam determining how many jacks shall be operated by said dog during the traverse of the jack-set thereby. It will be understood that the dog maintains its depressed ineffective position while traversing the jack-set, until the elevating cam encounters the stationary cam and is raised thereby to effective position, as at Fig. 2, whereupon it will maintain such position while it traverses the remaining jacks in the set.

An assortment of these denomination-selecting dogs may be provided for the machine, as seen in the drawings, some having short cams, some having cams of medium length, and some having cams of a length equal to the width of the entire set of denomination jacks. Hence, the operator is enabled, if required, to perform a variety of work, so as to use each register sometimes for close narrow-column work, and sometimes for wide-column work, etc. The dogs which are out of use may be slipped to one end of the supporting rod 37, where they will not be in position to engage any of the jacks; or, from time to time, one or more dogs may be removed entirely from the machine and others substituted, provision being illustrated in said patents for permitting removal of dogs.

At Fig. 2, there are illustrated complete sets of jacks 28 belonging to two registers, and the selecting dog 27 for one register B

is shown as having passed idly the jacks of upper denominations, and as having been cammed up into position to lift the jack of hundreds denomination; the elevating cam 40 of said dog having just been engaged 70 and elevated by means of the stationary cam 41, as seen. During the writing of the number upon the work-sheet, said dog will proceed to lift the tens jack, and then the units jack. The typewriter carriage will 75 then be advanced idly one space, by means of the usual spacing key at the front of the keyboard. During a portion of the described travel of the first dog, a second dog seen at said figure traversed some of 80 the jacks belonging to the second register A, but without engaging any of said jacks, since its elevating cam 40 had not yet reached the stationary cam 41 belonging to said set of jacks. In other words, no jack 85 will be raised by either dog during the first portion of its traverse, and no jack will be raised by the second dog while the first dog is raising the last three jacks in the first set. Then the second dog, whose cam 40 90 now comes into engagement with the stationary cam 41 of the second jack-set, will then raise *seriatim* the last three jacks in said second set. Hence, the numbers put in the second column, while the second dog is 95 lifting the last three jacks in its set, may be typed closely to the numbers that were typed in the first column; these columns being separated by no more than a single letter-space, if desired. Thus there is effected economy of space upon the work-sheet, where it has been the general practice heretofore to separate widely the narrow columns upon the work-sheet, so as to allow each dog to traverse idly all of the 100 unused higher-denomination jacks in the register.

At Fig. 8, the jacks 28 for one register are represented at A, those for another at B, and those for another at C. The jacks 110 at B are longer than those at A, and the jacks at C are longer than those at B. The dogs 27 are correspondingly located upon their mounts 36, so that each dog is capable of operating only the jacks of its associated set, and will pass idly by the jacks of the other sets. A similar variation in the lengths of jacks and the locations of dogs is described in said Hart Patents 1,190,171, 1,190,233, and 1,231,523. The 115 jacks in the three sets are also illustrated in elevation at Fig. 3, which also shows the locations of their respective selecting dogs. Since the stationary cams 41 for the jack-sets A, B and C are all in line, it happens 120 that the dogs are elevated idly by these cams, except when any dog is traversing its own set of jacks. It will be understood that where in any figure of the drawings two or three registers or jack-sets are indi- 130

cated, they may be provided with different lengths of jacks, as in Fig. 8, and the advantage is retained for each register (or each set of jacks) of permitting its associated dog to traverse idly certain jacks in the set, while elevating others thereof, so that in each set, the advantages are gained that are set forth elsewhere in this description.

10 At Fig. 5, A represents diagrammatically a cross-totalizer or register (or set of jacks) for numbers that are added vertically in column-registers B and C. The jack of thousands denomination for the column-register B is shown as raised by the dog D, whose elevating cam 40 has just come into engagement with the stationary cam 41. This cam 40 is similar to those seen at Fig. 4, but instead of being in roll form, it is in the form of a plate or downward extension of the bracket 43. At the same time, the first dog for operating the register A is shown at E as elevated by cams 40, 41, and holding up the thousands jack in set A. As 15 the number is typed, the aforesaid dogs D, E, will elevate in turn the hundreds, tens and units jacks on the registers A and B. Thereupon, dog F will, by means of its cam 40, be forced to elevate the thousands or 20 hundreds jack for the register C, and, at the same time, the second dog G for the register A will be forced to elevate the corresponding jack, so that the numbers added vertically in registers B and C are 25 cross-added in register A. It will be understood that the narrow columns corresponding with B and C may be typed closely together upon the work-sheet, for reasons already given, notwithstanding the fact 30 that while dogs are traversing jacks in both A and C, other dogs are elevating jacks at A and B.

At the right-hand part of Fig. 7, is illustrated an arrangement whereby registers 40 may be used for computing in one register numbers in three narrow columns which are typed closely together upon the work-sheet. The first dog at H is seen cammed up to hold up the jack 28 of hundreds denomination. While the operator proceeds to type numbers in the corresponding column on the work-sheet, said dog elevates the tens and units jacks, whereupon the second dog I engages its stationary cam 45 and is caused thereby to elevate the seventh jack from the right at said set C. In ordinary use of this register at C, that would be the millions jack, but in the present instance, it serves as a hundreds jack, 50 so that as the number is typed in the second column, this dog I proceeds to elevate the succeeding two jacks, which are now used as the tens and units jacks; whereupon the dog I passes by its stationary cam 45 and 55 falls into ineffective position, and thereafter

traverses idly the remaining jacks in the set. While said second dog I is thus traversing said remaining jacks, the third dog J reaches and is lifted by its stationary cam 46 to elevate the extreme left-hand jack in the set C, 70 which is likewise used for hundreds denomination, so that, as the operative proceeds to write a number in the third column, said third dog J proceeds to elevate the next two jacks, which are used as tens and hundreds 75 jacks at this time; and then said dog J may pass idly by the remaining jacks in said set C. Thus, register C is practically split into three registers by the use of the three dogs H, I, J, and the three pairs of cams. 80 It should be observed that the stationary cams 41, 45, 46 (Fig. 7^a) are not in line, so that the dog H can be elevated only by its stationary cam 41, the dog I only by its stationary cam 45, and the dog J only by its 85 stationary cam 46, so that this staggered, offset or echelon arrangement of the cams permits the splitting of the register into several parts. It will be understood, of course, that the elevated cams 40 upon the dogs H, 90 I, J are also in echelon, each elevating cam being in line only with its associated stationary cam. Moreover, these three dogs are out of line with the jacks in the other sets A and B (if the same are present on 95 the machine). Hence, the selection of different portions of a split register is effected by having the cams in staggered or echelon relation, while the selection of registers is effected by having the jacks of each set of 100 different length from those in the other sets.

At Fig. 6 is illustrated diagrammatically a method of cross-adding in register A the numbers that are vertically added in three columns in totalizer C, split as just explained. 105 In the cross-register at A only the three lowest jacks are brought into use at this time. These are brought into play repeatedly by means of the three dogs shown at K, L, M, these dogs being elevated one after another 110 by the single stationary cam 45. The three dogs H, I, J, for the register at C, Fig. 6, operate their respective jacks in the manner just above explained, so that the three narrow columns may be typed closely together 115 upon the sheet and added vertically in the single register C, and cross-added in the register A, which, if desired, may be used as a grand-totalizer. It will be understood that, if desired, the totalizer A may be provided 120 with staggered stationary cams 41, 45, 46, as seen at C, but that, when the elevating cams 40 of dogs K, L, and M are in alignment with cam 45 as shown in Fig. 6, the cams 45 and 46 will be idle.

Reference is again made to Fig. 7, to illustrate the vertical addition of numbers in six narrow columns by the use of only two registers, as B and C. The operation of the register C at this figure has already 125 130

been explained; and it will be seen further that immediately after the escape of the third dog J past the third jack from the left at C, the first of the three dogs marked N, 5 O, P will engage the third jack from the left in the set B, both being elevated by the stationary cam 41 (as at H). Then the operation will proceed for totalizer B in the manner above described in connection with 10 the totalizer C at said Fig. 7. The single register C is thus used for the addition of three closely placed separate narrow columns, while the register B is used for the addition of three more separate narrow columns typed closely to one another and to 15 the first three columns. This is permitted because the typewriter carriage has sufficient travel to enable the use of many adding zones; the jacks of C and dogs H, 20 I, J being, of course, idle when the jacks at B and dogs N, O, P are active. It will be understood at Fig. 7 that the dog-carrying rod 37 and the rack 39 may be extended to the left as far as necessary in order to enable 25 the dogs N, O, P to be properly adjusted with respect to the set of jacks of B. While there are illustrated at Fig. 7 only two registers, it will be understood that certain 30 features of the invention have advantages not only in connection with two-register machines, but also in connection with one-register machines, as well as in connection with machines having three or more registers.

35 At Fig. 1 is illustrated diagrammatically a single register Q, having say thirteen jacks and dials. This register is used not only for adding in two narrow columns, typed closely together on the page, but also for 40 cross-adding or securing the grand total of the numbers written in said columns. The first dog R is seen as thrust up by its stationary cam 41 to elevate the jack of thousands denomination, while the second dog S 45 is thrust up by its stationary cam 46 to elevate the extreme left-hand jack in the register, which is now also used for the thousands denomination. As the number is typed, these dogs progress toward the right 50 at Fig. 1, and each operates three more jacks for hundreds, tens and units denominations. Then the dogs slip off from the stationary cams 46 and 41, so that the number is vertically added at the right-hand 55 portion of the register and cross-added at the left-hand portion. Then the same dog S, which has two elevating cams 40, in line respectively with cams 45, 46, Fig. 2^b, is still held elevated by the stationary cam 45, after 60 it passes the stationary cam 46, and proceeds to elevate successively the sixth, seventh, eighth and ninth jacks from the left of Fig. 1, and a third dog T now engages the four jacks at the extreme left of the 65 register, to cross-add the number which is being added vertically in the middle portion of the register. This third dog T is elevated by stationary cam 46. If desired, an additional dog U, seen at the extreme left of Fig. 1, may be used subsequently for 70 operating the four jacks at the extreme left of the register, for subtracting the cross total.

When it is desired merely to cross-add, the arrangement seen at A at the left-hand portion of Fig. 6 can be used, without the totalizer C, or its three dogs H, I, J. The dogs K, L, M, which operate A, may be placed as closely together as desired, and many more dogs can be placed at their left, 75 each of which will be raised by the stationary cam 41 in turn, so as to operate the last three jacks in the set A. Thus, very many narrow columns may be written closely upon the work-sheet, and cross-addition thereof 80 performed. If any of the columns is wide, then there may be used for such column a dog having a longer cam, such as seen at D, Fig. 5, or a still longer one, as seen at Fig. 4. Each of the totalizers A, B and C may be 85 permanently provided with all three of the staggered stationary cams 41, 45, 46, ready to coöperate with appropriate dogs with which the machine may be equipped from time to time. Of course, each of the three 90 cams 41, 45, 46 will elevate the dogs which belong not only to its own register, but also those which are intended to operate the other registers, but such elevation will be idle, since the dogs are not in position to 95 engage the jacks at such times.

At Figs. 4 and 8, the register C is split in the manner described, one portion to be used only for vertical adding, while the numbers added vertically in the other portion are 100 also cross-added. The four right-hand jacks at C are operable by the first dog V, which is elevated by the stationary cam 41. The four left-hand jacks at C are operable by the dog W, which is elevated by the stationary 105 cam 45. The amount added by means of these four left-hand jacks may be cross-added in connection with amounts which are added in the register at B; the cross-adding register being indicated at A. All of the 110 jacks at B are liftable by its dog X, and all of the jacks at A may be elevated by each of dogs Y, Z. The extreme left-hand dog at Fig. 4 may be used for subtracting the 115 total from the cross-adder or grand-totalizer 120 A. The numbers added in the right-hand portion of register C are not cross-added.

The foregoing gives only a few illustrations of numerous uses to which the invention is adaptable.

125 Since it is not desired to perform computation when the case-shifting mechanism of the typewriter is shifted for writing capital letters, the stationary cams 41, 45, 46 for each register are mounted to be 130

dropped out of the way at the case-shifting operation. For this purpose, said cams are mounted upon the cross-arm 47 of a bail, whose side arms 48 extend rearwardly and 5 are mounted on rock-shaft 49 supported in the framework. The bail may be swung up and down by means of an arm 50 which extends up from a rock-shaft 51 and has a pin 52 to engage a cam slot 53 extending along 10 an arm 53^a, said cam slot being of a form for normally locking the bail up in effective position, the arm being held in normal position by a returning spring 54. This rock-shaft is operable by means of a pendent 15 arm 55, which is engaged by an arm 56 extending rearwardly from a rock-shaft 57 of the case-shifting mechanism 58, which may be the same as set forth in said Gumprecht Patent No. 1,268,565. Said rock-shaft for 20 silencing the dogs may likewise be operated by means of a bell-crank whose horizontal arm 59 engages a shoulder 60 provided upon the shaft 51; the depending arm 61 of said bell-crank being connected to a rod 62 ex- 25 tending forwardly and having a non-add key 63 at its forward end, as set forth in said Gumprecht Patent No. 1,268,565; and it will be further understood that said rock-shaft 51 may be operated by the tabulating 30 mechanism, as also set forth in said patent. There is provided one bail 47, 48 for each of the registers, and all of the bails are fixed upon their rock-shaft 49, so that all of the adding mechanisms are silenced at the case- 35 shifting operation, or at the operation of the non-add key, or at the back-spacing operation, or at the tabulating operation, etc.

The cams may be detachably secured to the dogs by screws 64 as shown, so as to be 40 interchangeable so that by having a number of bodies and an assortment of cams, any desired system of dogs may be provided, thus conduceing to economy. It will be understood that four or more registers may 45 be employed. Where in the claims the word "jacks" is used, it is intended to include not only the levers shown, but also any kind of device whereby the selection of denominations can be effected; and it is not 50 necessary in all cases that the dog or equivalent device engage directly with the jack or equivalent device.

Variations may be resorted to within the scope of the invention, and portions of the 55 improvements may be used without others.

Having thus described my invention, I claim:

1. In an adding machine having a set of 60 denomination jacks, the combination of a normally ineffective jack-selecting dog in line with all of said jacks, a carriage to cause relative traverse between the dog and jacks, means for mechanically determining with how many of said jacks said dog may

coöperate, a succeeding dog, and other 65 means for mechanically determining with how many jacks said succeeding dog may coöperate.

2. In an adding machine having a set of 70 denomination jacks, the combination of a normally ineffective jack-selecting dog in line with all of said jacks, a carriage to cause relative traverse between the dog and jacks, means for mechanically determining with how many of said jacks, less than the 75 whole number thereof, said dog may coöperate, a succeeding dog, and other means for mechanically determining with how many jacks, less than the whole number thereof, said succeeding dog may coöperate. 80

3. In an adding machine having a set of 85 denomination jacks, the combination of a normally ineffective jack-selecting dog in line with all of said jacks, a carriage to cause relative traverse between the dog and jacks, means mounted at one portion of said jack set for mechanically determining with how many of said jacks at said portion said dog may coöperate, a succeeding dog incapable of coöperation with said determining 90 means, and means mounted at another portion of said jack set for mechanically determining with how many of the jacks at said other portion said succeeding dog may coöperate. 95

4. In an adding machine having a set of 100 denomination jacks, the combination of a succession of normally ineffective jack-selecting dogs, a letter-feeding carriage to cause relative traverse between the dogs and jacks, elevating cams or devices upon said dogs, each of said cams of a length to determine the number of jacks that may be selected by its dog, and a stationary cam or device incapable of determining the number 105 of jacks to be selected by any dog, but capable of coöoperating with all of said elevating cams.

5. In an adding machine, the combination 110 with a set of denomination jacks, of a series of normally ineffective jack-selecting dogs, a letter-feeding carriage to cause relative traverse between the dogs and jacks, elevating cams or devices upon said dogs, the effective extent of the elevating cams on certain 115 of said dogs being substantively less than the width of the set of jacks, and a stationary cam or part to coöperate with said elevating cams successively during a single run of said carriage. 120

6. In a combined typewriting and adding machine having a carriage and a succession of sets of denomination jacks, the combination of a succession of normally ineffective denomination-selecting dogs, each dog having individual means for determining with how many jacks, less than the whole number in a set, it may coöperate, and means indi- 125

vidual to said jack sets to cooperate with the carriage for moving said dogs in succession to effective positions.

7. In an adding machine having a carriage, the combination of a succession of sets of denomination jacks, the jacks in one set out of line with the jacks in another set, a succession of normally ineffective adjustable denomination-selecting dogs to coöperate respectively with said sets of jacks, each dog in line with only its associated set of jacks, and means adjustable with each dog for determining with how many jacks in its set said dog may coöperate.
- 15 8. In an adding machine having a carriage and a succession of sets of denomination jacks, the combination of a succession of normally ineffective adjustable denomination-selecting dogs to coöperate respectively with said sets of jacks, each dog incapable of coöperation with any jacks save those in its associated set, cams or devices individual to said dogs for determining mechanically with how many jacks the dog 25 may coöperate, and cams or devices associated with said jack sets for coöperating with said dog cams.

9. In an adding machine having a carriage and a set of denomination jacks, the combination of a succession of normally ineffective denomination-selecting dogs, means to enable one of said dogs to select jacks at only one portion of the set, and means to enable another of said dogs to select jacks at 35 only another portion of the set.

10. In an adding machine having a carriage and a set of denomination jacks, the combination of a succession of normally ineffective denomination-selecting dogs, means 40 to enable one of said dogs to select jacks at only one portion of the set, means to enable another of said dogs to select jacks at only another portion of the set, and means to enable still another of said dogs to select jacks at only a third portion of the set.

11. In an adding machine having a carriage and a set of denomination jacks, the combination of a succession of normally ineffective denomination-selecting dogs, means 50 to enable one of said dogs to select jacks at only one portion of the set, and means to enable another of said dogs to select jacks at only another portion of the set; each of said dogs having provision for determining 55 how many jacks, less than the entire number of jacks, in the set, it may select.

12. In an adding machine having a set of denomination jacks, the combination of a succession of normally ineffective denomination-selecting dogs, each dog provided 60 with a cam or device for determining how many denominations may be selected thereby, and a succession of cams or devices out of line with each other and associated with

said sets of jacks, said dog cams being respectively in line with said jack cams to coöperate therewith to move the dogs to effective positions at different portions of the set of jacks.

13. In an adding machine having a set of denomination jacks, the combination of a succession of normally ineffective denomination-selecting dogs, each dog provided with a cam or device for determining how many denominations may be selected thereby, and a succession of cams or devices associated with said set of jacks, one of said dogs capable of coöperation with only one of said associated cams or devices, and another of said dogs capable of coöperation with only another of said associated cams or devices.

14. In a combined typewriting and adding machine having a carriage and a succession of sets of denomination jacks, the combination of a succession or group of normally ineffective denomination-selecting dogs, means to enable one of said dogs to select jacks at only one portion of the first of the jack sets, means to enable another of said dogs to select jacks at only another portion of the first jack set, a second succession or group of denomination-selecting dogs, means to enable one of said dogs in the second group to select jacks at only one portion of the second jack set, and means to enable another of said dogs in the second group to select jacks only at another portion of the second jack set.

15. In a combined typewriting and adding machine having a carriage and a succession of sets of denomination jacks, the combination of a succession or group of normally ineffective denomination-selecting dogs, means to enable one of said dogs to select jacks at only one portion of the first of the jack sets, means to enable another of said dogs to select jacks at only another portion of the first jack set, a second succession or group of denomination-selecting dogs, means to enable one of said dogs in the second group to select jacks at only one portion of the second jack set, and means to enable another of said dogs in the second group to select jacks only at another portion of the second jack set; each of the dogs in each of the groups having provision for determining with how many jacks it may coöperate.

16. In a combined typewriting and adding machine having a carriage and a succession of sets of denomination jacks, the combination of a succession or group of normally ineffective denomination-selecting dogs, means to enable one of said dogs to select jacks at only one portion of the first of the jack sets, means to enable another of said dogs to select jacks at only another

portion of the first jack set, a second succession or group of denomination-selecting dogs, means to enable one of said dogs in the second group to select jacks at only one portion of the second jack set, and means to enable another of said dogs in the second group to select jacks only at another portion of the second jack set; each of the dogs in each of the groups having provision for determining with how many jacks it may coöperate; the jacks in one set being of different length from the jacks in another set, and the dogs in the different groups being differently located to enable each dog to coöperate only with jacks in its associated set.

17. In a combined typewriting and adding machine having a carriage and a set of denomination jacks, the combination of a succession of normally ineffective adjustable denomination-selecting dogs, each having a cam or device for determining with how many jacks it may coöperate, and means at said jack set to coöperate with said cam or device to move said dogs to effective position in succession after traversing the jacks with which said dogs may not coöperate, said dogs with their cams having an aggregate width not substantially greater than the width of the jack set, to permit typing closely together upon the work-sheet narrow columns of the computed numbers.

18. In an adding machine having a set of denomination jacks, the combination of a normally ineffective jack-selecting dog in line with all of said jacks, a carriage to cause relative traverse between the dog and jacks, means mounted at one portion of said jack set for mechanically determining with how many of said jacks at said portion said dog may coöperate, a succeeding dog incapable of coöperation with said determining means, means mounted at another portion of said jack set for mechanically determining with how many of the jacks at said other portion said succeeding dog may coöperate, a set of cross-adding jacks, a succession of cross-adding selecting dogs capable of traversing one portion of said cross-adding jacks while ineffective, and means for rendering said cross-adding dogs effective successively at another portion of said set of cross-adding jacks.

19. In a combined typewriting and adding machine having a carriage and a succession of sets of denomination jacks, the combination of a succession of normally ineffective denomination-selecting dogs, each dog having individual means for determining with how many jacks, less than the whole number in a set, it may coöperate, means individual to said jack sets to coöperate with the carriage for moving said dogs in succession to effective positions, a set of cross-adding

dogs capable of traversing one portion of said cross-adding jacks while ineffective, and means for rendering said cross-adding dogs effective successively at another portion of said set of cross-adding jacks.

20. In an adding machine having a carriage, the combination of a succession of sets of denomination jacks, the jacks in one set out of line with the jacks in another set, a succession of normally ineffective adjustable denomination-selecting dogs to coöperate respectively with said sets of jacks, each dog in line with only its associated set of jacks, means adjustable with each dog for determining with how many jacks in its set said dog may coöperate, a set of cross-adding jacks, a succession of cross-adding-selecting dogs capable of traversing one portion of said cross-adding jacks while ineffective, and means for rendering said cross-adding dogs effective successively at another portion of said set of cross-adding jacks; the jacks in said cross-adding set being of different length from the jacks in either of the other sets.

21. In an adding machine having a carriage and a succession of sets of denomination jacks, the combination of a succession of normally ineffective adjustable denomination-selecting dogs to coöperate respectively with said sets of jacks, each dog incapable of coöperation with any jacks save those in its associated set, cams or devices individual to said dogs for determining mechanically with how many jacks the dog may coöperate, and cams or devices associated with said jack sets for coöoperating with said dog cams; one of said sets of jacks having associated therewith an additional dog, whereby cross-adding may be performed of numbers added by the aid of the jacks in the other sets.

22. In an adding machine having a carriage and a set of denomination jacks, the combination of a succession of normally ineffective denomination-selecting dogs, means to enable one of said dogs to select jacks at only one portion of the set, means to enable another of said dogs to select jacks at only another portion of the set, and means to enable a certain plurality of said dogs to select jacks at a third portion of the set, for performing cross-addition of numbers added in the first and second portions of the set.

23. In a typewriting and adding machine having a carriage and a set of denomination jacks, the combination of a succession of normally ineffective denomination-selecting dogs, a dog-controlling device including means to enable one of said dogs to select jacks at only one portion of the set, a second dog-controlling device including means to enable another of said dogs to select jacks at

only another portion of the set, and means for silencing said dog-controlling devices simultaneously.

24. In an adding machine having a set 5 of denomination jacks, the combination of a succession of normally ineffective denomination-selecting dogs, each dog provided with a cam or device for determining how many denominations may be selected there-
10 by, a succession of cams or devices out of line with each other and associated with said set of jacks, said dog cams being respectively in line with said jack cams to coöperate therewith to move the dogs to ef-
15 fective positions at different portions of the set of jacks, and means for shifting said jack cams simultaneously to ineffective po-
sitions.

25. In a combined typewriting and add-
20 ing machine having a carriage and a succession of sets of denomination jacks, the combination of a succession of normally ineffect-
ive denomination-selecting dogs, each dog having individual means for determin-
25 ing with how many jacks, less than the whole number in a set, it may coöperate, means individual to said jack sets to coöperate with the carriage for moving said dogs in succession to effective positions, and means
30 to silence all of said individual means simul-
taneously.

26. In an adding machine having a carriage, the combination of a succession of sets of denomination jacks, the jacks in one
35 set out of line with the jacks in another set, a succession of normally ineffective adjustable denomination-selecting dogs to coöperate respectively with said sets of jacks, each dog in line with only its associated set of
40 jacks, means adjustable with each dog for determining with how many jacks in its set said dog may coöperate, a device at each jack set to enable coöperation between a dog and the jacks, and means for simul-
45 taneously silencing said devices at the jack sets.

27. In an adding machine having a carriage and a succession of sets of denomina-
50 tion jacks, the combination of a succession of normally ineffective adjustable denomina-
tion-selecting dogs to coöperate respectively with said sets of jacks, each dog incapable of coöperation with any jack save those in its associated set, cams or devices
55 individual to said dogs for determining me-
chanically with how many jacks the dog may coöperate, cams or devices associated with said jack sets for coöoperating with said dog cams, and means operating auto-
60 matically at the performance of another function of the machine, for simultaneously silencing the cams or devices associated with said jack sets.

28. In an adding machine, the combina-

tion with a letter-feeding carriage and a 65 set of jacks, of a normally ineffective dog adjustable along said carriage and provided with a cam adjustable therewith and ex-
tending in the direction of the run of the carriage for determining how many jacks 70 in the set may coöperate with said dog, and a coöoperating cam or device associated with said set of jacks.

29. As a new article of manufacture, a 75 denomination-selecting dog for actuating a series of denominational members *seriatim*, having provision whereby it may be set to operate at different positions in the line of typing, and provided with a cam extending in the direction of the line of typing 80 for a plurality of letter-spaces, whereby said dog may be moved from normal ineffective position to effective position; the length of said cam being determinative of the number of selections to be made by said dog. 85

30. As a new article of manufacture, an adjustable normally ineffective denomina-
tion-selecting dog for actuating a series of denominational members *seriatim*, provided with ears, and a cam roll journaled in said 90 ears and extending for a plurality of letter-
spaces in the direction of the travel of the dog, whereby said dog may be moved from normal ineffective to effective position, the length of said cam roll being determinative 95 of the number of selections to be made by said dog.

31. In a combined typewriting and add-
ing machine, the combination with denomina-
tion jacks, of a succession of denomina-
tion-selecting dogs, each of said dogs hav-
ing cams to determine with how many jacks 100 it may coöperate, devices associated with
the jacks and out of line with each other for determining where dogs may coöperate with 105 jacks, said dogs having said cams in line with one of said associated devices, and one of said dogs also having a cam in line with the other of said associated devices.

32. As a new article of manufacture, an 110 adjustable denomination-selecting dog for an adding machine, having a plurality of cams out of line with each other, for co-
operating with staggered dog-elevating de-
vices to determine how many denomina-
tions may be selected by said dog when each 115 of the cams thereon is in use.

33. An assortment of denomination-se-
lecting dogs having interchangeable cams for determining how many denominations 120 the dogs may respectively select.

34. An assortment of denomination-se-
lecting dogs having interchangeable cams for determining how many denominations the dogs may respectively select, said cams 125 being out of line with one another, to co-
operate with cam-elevating devices having staggered or echelon arrangement.

35. In a computing machine, the combination with a traveling carriage, of a computing unit comprising a series of denominational jacks, having in alinement the ends through which they are actuated, a plurality of denomination-selecting dogs mounted on said carriage, to move therewith past said jacks, and normally positioned so as to pass said jacks without actuating the same, and means whereby said dogs will be moved into operative position in passing different groups of said jacks, thereby obtaining, in effect, a splitting of said computing unit.

BURNHAM C. STICKNEY.
